MOTORCYCLE HAND GRIP OR THE LIKE

George A. Johnson, 27239 Barada Ave.,
Saugus, Calif. 91350

Filed Apr. 24, 1975, Ser. No. 571,377

Term of patent 14 years

Int. Cl. D12—11

U.S. Cl. D8—138

Fig. 1

Fig. 2

Fig. 3

FIG. 1 is a plan view of a motorcycle hand grip or the like embodying the claimed design;

FIG. 2 is a side elevational view thereof; and

FIG. 3 is an end view thereof.

In the figures, the dashed lines indicate the handlebar per se and form no part of the present invention.

I claim:

The ornamental design for a motorcycle hand grip or the like, substantially as shown and described.
